UNITED STATES PATENT OFFICE.

LEWIS WEHNER, OF MILWAUKEE, WISCONSIN, ASSIGNOR TO PAWLING AND HAR-NISCHFEGER COMPANY, OF WEST MILWAUKEE, WISCONSIN, A CORPORATION OF WISCONSIN.

EXCAVATOR CRANE.

Application filed February 20, 1922. Serial No. 537,676.

To all whom it may concern:

Be it known that I, Lewis WEHNER, a citizen of the United States, residing at Milwaukee, in the county of Milwaukee and State of Wisconsin, have invented certain new and useful Improvements in Excavator Cranes, of which the following is a specification, reference being had to the accompanying drawing, forming a part 10 thereof.

This invention relates more particularly to portable power shoveling machines of the boom and dipper type.

Its main objects are to simplify and improve 15 the construction and facilitate the operation of machines of this class, particularly with relation to the mechanism for operating and controlling the movements of the dipper or scoop.

It consists in the construction, arrangement and combination of parts as herein-after particularly described and pointed out 20 in the claims.

In the accompanying drawing like 25 characters designate the same parts in the several figures.

Figure 1 is a side elevation of an excavator crane or portable power shoveling machine embodying the invention; Fig. 2 is 30 an enlarged section on the line 2—2, Fig. 1; Fig. 3 is a similar section on the line 3—3, Fig. 1; Fig. 4 is an enlarged side elevation of mechanism for shifting the dipper relative to the boom lengthwise of the dipper arm; and Fig. 5 is a vertical cross section of such mechanism on the broken line 35 5—5, Fig. 4.

Referring to Fig. 1, the machine comprises a truck or carriage 1, which may be 40 of the link belt tread type or other suitable construction, a horizontally swinging platform, frame or body 2, a vertically adjustable boom 3, hinged or pivoted at one end to the front end of the body 2 and connected therewith by adjustable braces 4, and a dipper 45 comprising a bucket or scoop 5, having a hinged dumping bottom 6, of the usual or any suitable construction, and a handle or arm composed of two parallel members 50 7, straddling the boom 3 and pivotally and slidably connected therewith.

The upper outer end of the boom 3 is 55 adjustably supported by a cable 9 wound on a drum 10 on the frame or body 2 and passing around guiding sheaves 11, mounted on

the frame above the drum, and sheaves carried by a yoke 12, which is pivotally connected with the boom.

The dipper arm members 7 are provided with parallel longitudinal racks 13, and are 60 pivotally and slidably connected with the boom 3 by a transverse shipper shaft 14, journaled in bearings 15 on the boom, and by saddle blocks 16, which are journaled or pivoted on the ends of the shipper shaft and 65 in which the members 7 of the dipper arm are supported and guided in proper relation to the boom, as shown in detail in Figs. 2 and 3.

A sprocket wheel 18 is fixed on the shipper shaft 14 between the bearings 15, and pinions 19 are fixed on said shaft at the outer sides of said bearings and mesh with the racks 13.

The dipper arm members 7 are for the 75 sake of flexibility, preferably made of hard wood and are faced with steel or metal reinforcing and wearing plates 20 and 21, which engage with the inner sides of the saddle blocks 16, angular guide and wearing bars 22 fastened to opposite sides of the boom, and steel or hard metal wearing shoes 23, fastened to the inwardly projecting ends 80 of the saddle blocks.

The frame or body 2, which carries the 85 boom and dipper, is swung horizontally by the usual or any suitable means such as a circular rack 25, fixed on the truck frame, and by a pinion 26, fixed on a vertical shaft 90 which is journaled in the swinging frame or body and may be rotated in opposite directions by suitable reversible power transmission connections (not shown in detail), with a gasoline engine or motor 27 mounted 95 on the swinging frame or body, as shown in Fig. 1.

The dipper arm is advanced and withdrawn lengthwise thereof relative to the boom, by a sprocket wheel or driving member 29, loosely mounted on a driving shaft 100 30, as shown in Fig. 5, and directly connected with the sprocket wheel 18 on the shipper shaft by a link belt 31, as indicated in Fig. 1. The shaft 30, which is mounted 105 on the swinging frame or body 2, parallel with the shipper shaft 14, is provided, as shown in Figs. 4 and 5, with a fast or fixed driving gear 33, and with fast or fixed and loose reversing gears 34 and 35.

Two pairs of axially connected planetary 110

- gears 37 and 38, meshing respectively with the fast and loose reversing gears 34 and 35, are mounted on the driving sprocket or member 29, which is provided at one end adjacent the driving gear 33 with a clutch drum 40, and at the other end with a brake drum 41. A clutch band 43, passing around the drum 40, is adjustably connected at one end with the gear 33, and is connected at the other end with one arm of a lever 44, which is fulcrumed in and carried by said gear, and the other arm of which is connected with the gear by a spring 45, which tends to expand the clutch band.
- 15 A cone collar 47, mounted on the shaft 30 and shiftable lengthwise thereof in engagement with the lever 44, is adapted when thrust towards the gear 33, to contract the band 43 on the drum 40, and thus lock or operatively connect the driving sprocket or member 29 with the driving gear 33. The collar 47 is connected by a lever 48 and adjustable link 49 with a clutch operating and controlling hand lever 50.
- 20 25 A brake band 51, passing around the drum 41, is connected at one end with a fixed part of the frame or body 2, and at the other end with an arm 52, indicated by dotted lines in Fig. 4, on a rocker shaft 53, provided with an arm 54, which is connected by a link 55 with a treadle or foot lever 56.
- 30 35 A differential clutch band 58, passing around a drum 59, fixed on the loose reversing gear 35 and crossing itself adjacent its ends, is connected with longer and shorter arms 60 and 61, on a rocker shaft 62, the connection of the band with one of the arms being adjustable.
- 35 40 45 50 55 60 65 70 75 80 85 90 95 100 105 110 115 120 125 130 A weight 64, suspended from an arm 65 on the rocker shaft 62, is connected with one arm of a lever 66, the other arm of which is connected by a link 67 with the treadle or foot lever 56, so that when the clutch band 58 is contracted on the drum 59, to render the planetary reversing gearing operative for reversing the rotation of the driving sprocket wheel or member 29, the brake band 51 will be expanded, leaving said sprocket wheel or member free to rotate on the shaft 30.
- 75 80 85 90 95 100 105 110 115 120 125 130 The treadle or foot lever 56 is provided with a pivoted latch or detent 69, which is held by a spring 70 normally in engagement with a shoulder on a segment 71 attached to the frame or body 2, as shown in Fig. 5. In this, the neutral position of the treadle or foot lever 56, the brake band 51 and the clutch band 58 are both expanded and held by the weight 64 out of operative engagement with the drums 41 and 59, thus leaving the driving sprocket wheel or member 29 free to be rotated with the driving shaft 30 and gear 33, in the direction indicated by a full line arrow in Fig. 4.

When the latch 69 is disengaged from the shoulder on the segment 71, the weight 64 will contract the clutch band 58, and effect initial engagement thereof with the drum 59, thereby holding the loose reversing gear 35 against rotation with the shaft 30, and causing the planetary reversing gearing to rotate the sprocket wheel or driving member 29 in a direction, indicated by a dotted arrow in Fig. 4, reverse to that of the driving shaft 30 and driving gear 33. At the same time, the brake band 51 is held by the connection of the rocker shaft 53 through the treadle or foot lever 56 with the weight 64 hereinbefore described, out of operative engagement with the drum 41, thereby leaving the driving sprocket wheel or member 29 free to be rotated in a direction reverse to that of the driving shaft 30.

The construction and arrangement of the differential clutch band 58 and its connections with the rocker shaft 62 are such that when the band is contracted and brought into initial engagement with the drum 59, the tendency of the drum to rotate with the driving shaft 30 in the direction indicated by full line arrow, Fig. 4, will tighten the band on the drum with increasing force the greater the power transmitted through the reversing gearing, to withdraw the dipper scoop 5 towards the boom 3. By depressing the treadle or foot lever 56 to carry the latch or detent 69 below the shoulder on the segment 71, the brake band 51 will be contracted on the drum 41 to lock and hold the driving sprocket or member 29 against rotation in either direction. At the same time, the weight 64 will be lifted, thereby releasing the grip of the clutch band 58 on the drum 59.

The dipper scoop 5 is swung with the arm 7 forwardly and upwardly on the shipper shaft 14, by a cable 72 attached at one end to the boom 3, passing thence downwardly around a sheave 73 connected with the scoop, thence upwardly around a sheave 74, mounted in the upper end of the boom 3, and thence to a hoisting drum 75, to which it is attached, and which is mounted on the frame or body 2, parallel with the shaft 30, with which it is connected by a gear 76 meshing with the gear 33.

The gear 76 is connected by suitable transmission gearing with the engine 27, as indicated in Fig. 1, and transmits power from the engine through the gear 33 to the driving shaft 30. A clutch or mechanism like or similar to that shown in Figs. 4 and 5 for connecting the sprocket wheel or driving member 29 with the gear 33, is provided for connecting the drum 75 with the gear 76 under the control of a hand lever 77, shown in Fig. 1.

In operation the machine is moved about and advanced on the truck 1 to carry the

boom and dipper in proper working position as the work progresses.

The dipper is thrust into or against the material to be shoveled or scooped up, as for instance a bank of gravel, by swinging the hand lever 50 outward, thereby operatively connecting the sprocket wheel 29 with the driving gear 33, the brake band 51 and clutch band 58 being held out of operative engagement with the drums 41 and 59 by the weight 64 and the latch 69. The gear 33 being constantly turned with the shaft 30 in the same direction by the engine 27, when the sprocket wheel is clutched to the gear as above stated, the scoop 5 will be shifted lengthwise of the dipper arm from the boom by the pinions 19 on the shipper shaft 14 engaging the racks 13 on the dipper arm members 7. The dipper is then swung upward by the hoisting drum 75 and cable 72 connected with the scoop 5, under the control of the lever 77, while the scoop is held in digging position under the control of the lever 50, till the scoop is filled, when it may be lifted still further and shifted, if necessary, further away from the boom, while it is swung with the boom to one side or the other for dumping into a car or truck, or depositing the material in a convenient place.

The scoop 5 may be held at a fixed distance from the shipper shaft 14 by releasing the clutch band 43 controlled by the lever 50, and by depressing the foot lever 56, which applies the brake band 51 to the drum 41, while the clutch band 58 is held out of operative engagement with the drum 59 and the planetary reversing gearing is thus rendered inoperative by the connections hereinbefore described of the brake and clutch bands with the foot lever 56.

While the dipper arm is thus held against longitudinal movement relative to the boom 3, the dipper may be swung up or down on the shipper shaft 14, as a pivot to raise or lower the scoop 5, by means of the hoisting drum 75, the operation of which is controlled by a clutch and brake (not shown) like or similar to those shown for controlling the operation of the sprocket wheel 29.

After the scoop has been dumped, it is returned to take up another load, by a reversal of the operations above described, the scoop 5 being withdrawn lengthwise of the dipper arm towards the boom by applying the clutch band 58 to the drum 59, which brings the planetary reversing gearing into operation while the brake band 51 is held released, the clutch band 43 having been released with the lever 50.

The construction and arrangement of the pivotal and sliding connections between the dipper arm and the boom and of the dipper operating mechanism and connections,

avoids side thrust or strain on the boom and dipper arm, admits of grouping the controlling levers within convenient reach of the operator and clear view for his constant observation of the dipper, and admits of the use of a non-reversible gasoline or internal combustion engine, which is more economical and convenient than steam engines and other kinds of motors to operate in connection with machines of this class.

I claim:

1. In an excavator crane, the combination with a dipper arm and a constant speed non-reversible motor for operating the same, of a shaft interposed between said arm and motor and driven by the latter, a power transmitting member loosely mounted on said shaft and connected to said arm, and means arranged on said shaft for driving said member in either direction.

2. In an excavator crane, the combination with a dipper arm and a constant speed non-reversible motor for operating the same, of a shaft interposed between said arm and a motor and driven by the latter, a power transmitting member loosely mounted on said shaft and connected to said arm, and independently controlled means interposed between said member and said shaft for rotating the former in either direction.

3. In an excavator crane, the combination with a dipper arm and a constant speed non-reversible motor for operating the same, of a shaft interposed between said arm and motor and driven by the latter, a power transmitting member loosely mounted on said shaft and connected to said arm, and independently controlled means interposed between said member and said shaft for rotating the former in either direction, said means being frictionally connectable with said member whereby the power may be applied gradually and the member driven at variable speeds.

4. In an excavator crane, the combination with a dipper arm and constant speed non-reversible drive shaft therefor, of a power transmitting member loosely mounted on said shaft and connected with said arm, and means also mounted on said shaft for rotating said member in either direction.

5. In an excavator crane, the combination with a dipper arm and constant speed non-reversible drive shaft therefor, of a power transmitting member loosely mounted on said shaft and connected with said arm, and means also mounted on said shaft for rotating said member in either direction, said means and said member being axially fixed with respect to said shaft and said means being operatively associated with opposite ends of said member respectively.

6. In an excavator crane, the combination

- with a dipper arm and constant speed non-reversible drive shaft therefor, of a power transmitting member loosely mounted on said shaft and connected with said arm, 5 means also mounted on said shaft for rotating said member in either direction, said means and said member being axially fixed with respect to said shaft and said means being operatively associated with opposite 10 ends of said member respectively, and friction bands for operatively connecting said means with said member.
7. In an excavator crane, the combination with a dipper arm and constant speed non-reversible drive shaft therefor, of a power transmitting member loosely mounted on said shaft and connected with said arm, means arranged on said shaft and associated with one end of said member for driving the 20 same in one direction, and means operated by said shaft and associated with the other end of said member for driving the same in the opposite direction.
8. In an excavator crane, a dipper arm, a driving member therefor, means for rotating said member at variable speeds in one direction, means for rotating the same at variable speeds in the reverse direction, and a constant speed non-reversible drive shaft common to said member and said means and on which the latter are located.
9. In an excavator crane, the combination with the boom, dipper handle, shipper shaft and driving connection between the latter and said shaft, of a drive shaft mounted on the body of said crane, a driving gear fixed thereto, means for driving said shaft at substantially constant speed, a driving member loosely mounted on said shaft and operatively connected with said shipper shaft, means for connecting said driving member with the driving gear to move the dipper arm in one direction, and planetary reversing gearing interposed between said driving member and said driving shaft for moving the dipper arm in the opposite direction.
10. In an excavator crane, the combination with the boom, dipper handle, shipper shaft and driving connection between the latter and said shaft, of a driving gear fixed thereto, means for driving said shaft at substantially constant speed, a driving member loosely mounted on said shaft and operatively connected with said shipper shaft, means for connecting said driving member with the driving gear to move the dipper arm in one direction, planetary reversing gearing interposed between said driving member and said driving shaft for moving the dipper arm in the opposite direction, and friction bands for operatively connecting said means with said member.
11. In an excavator crane, the combination with the boom, dipper handle, shipper shaft and driving connection between the latter and said shaft, of a drive shaft mounted on the body of said crane, a driving gear fixed thereto, means for driving said shaft at substantially constant speed, a driving member loosely mounted on said shaft and operatively connected with said shipper shaft, means for connecting said driving member with the driving gear to move the dipper arm in one direction, planetary reversing gearing interposed between said driving member and said driving shaft for moving the dipper arm in the opposite direction, a friction clutch for connecting said driving member with the driving shaft, a friction clutch for rendering the reversing gearing operative, a brake for holding said driving member against turning, and a lever connected with the brake and with the reversing clutch and adapted to release the brake when the reversing clutch is engaged.
12. In an excavator crane, the combination with the boom, dipper handle, shipper shaft and driving connection between the latter and said shaft, of a drive shaft mounted on the body of said crane, a driving gear fixed thereto, means for driving said shaft at substantially constant speed, a driving member loosely mounted on said shaft and operatively connected with said shipper shaft, means for connecting said driving member with the driving gear to move the dipper arm in one direction, planetary reversing gearing interposed between said driving member and said driving shaft for moving the dipper arm in the opposite direction, a friction clutch for connecting said driving member with the driving shaft, a friction clutch for rendering the reversing gearing operative, a brake for holding said driving member against turning, a weighted lever connected with the reversing clutch and with the brake and adapted to release the brake when the reversing clutch is engaged, and a latch for releasably holding said lever in neutral position.
- In witness whereof I hereto affix my signature.

LEWIS WEHNER.
